UNITED STATES PATENT OFFICE

DAVID PATERSON, OF TORONTO, ONTARIO, CANADA

STRUT FOR BRAKE BEAMS.

Application filed May 15, 1928. Serial No. 277,869.

The principal objects of this invention are to provide a strut for brake beams for railway cars which will enable the universal use of a main strut casting which can be used on right or left beams and to provide a beam structure which may be very easily and quickly assembled.

The principal feature of the invention consists in the novel construction of a strong, rigid strut formed with a squared end adapted to engage the beam with the lever slot sloping either right or left and the opposite end cross notched to embrace the brace rod whether turned right or left.

In the drawings, Figure 1 is a plan view of a brake beam shown in its relation to a pair of wheels and showing the mounting of the brake lever.

Figure 2 is an enlarged elevational view of the strut showing the lever slot.

Figure 3 is an enlarged elevational view of the strut taken at right angles to Figure 2.

Figure 4 is an enlarged cross sectional view through the strut and brake lever taken at the pivot pin.

Figure 5 is an enlarged perspective view of the strut, and Figure 6 is a perspective detail of a modified form of strut.

In railway practice it has been necessary for car shops and maintenance departments to maintain a supply of right and left brake beam struts and very much inconvenience with loss of time and tie-up of cars has resulted in the improper maintenance of stocks of right and left struts. It is the purpose of this invention to provide a strut which may be used for either right or left assembly.

In the construction of strut herein shown, the main body of the casting 1 is of an elongated rectangular form having a rectangular slot 2 arranged between two parallel side members 3 each reinforced with longitudinal edge flanges 4. The side members 3 converge at one end to a narrow neck portion 5 which is flared outwardly into a box-like structure 6 which has rectangular openings 7 arranged in right angular relation and extending completely through the box end 6 at right angles to the axis of the strut.

The openings 7 are adapted to receive the

channel bar beam 8 so that the lever slot 2 is inclined either to the right or to the left as may be desired.

A hole 9 encircled by a flange 10 is arranged in each of the side members 3 midway of their length to receive and hold the pivot pin 11 of the brake lever 12 which extends through the slot.

The outer end of the strut is flared to form a rectangular end which is recessed in the end face with right angularly intersecting semi-cylindrical grooves 13 arranged in parallel alignment with the openings 7 and these are adapted to receive and hold the angled brace rod 14, the ends of which pass angularly through the shoe heads 15 secured to the ends of the beam.

The device is extremely simple and by reason of its simplicity and rigid structure it is very easily and quickly assembled in a beam and when placed in position it may, if desired, be secured from longitudinal movement by a bolt 16 which may be passed through the web of the beam 8 and through the hole 17 in the end of the box end 6.

It will be readily seen that in assembling the component parts of a beam the strut herein described may be placed at either a right or left angle whichever may be desired and if in cases of emergency where an assembled beam is available but it is not the angle required it is a very simple matter to remove the brace rod and heads and reverse the strut.

In the form of the invention shown in Figure 6 the beam end of the strut is formed with a box-shaped end 18 adapted to fit between the flanges 19 of the channel compression member 8 of the beam and abut the web and it is secured in place by a bolt 20 passed through the flanges of said head.

What I claim as my invention is:—

1. A strut for brake beams, comprising the combination with the flanged beam, of a longitudinally slotted strut member having a rigid squared end integral therewith adapted to engage the flanges of said beam to lock said member rigidly in position with the slot at either a right or left inclined angle, said member having notches in the other end adapted to receive the brake beam brace rod.

2. A strut for brake beams, comprising the combination with the flanged beam, of a longitudinally slotted member having a box-shaped end formed integral therewith with right angularly disposed intersecting openings in the sides arranged in acute angular relation to the slot adapted to receive the flanged beam, said member having a right angularly notched outer end.
- 10 3. A strut for brake beams, comprising the combination with the flanged beam, of a longitudinally slotted member having a rectangular box-shaped end formed with rectangular openings extending therethrough and intersecting at right angles and arranged in acute angular relation to the slot, either of said openings being adapted to receive said flanged beam, the outer end of said slotted member having intersecting right angularly disposed slots, and a fastening bolt extending through the end wall of said box-shaped end and the web of said beam in axial alignment with said slotted member for securing the latter in its adjusted position on the beam.
- 15 4. A strut for brake beams, comprising the combination with the flanged beam, of a longitudinally slotted strut member having a rigid squared end integral therewith adapted to engage the flanges of said beam to lock said member rigidly in position with the slot at either a right or left inclined angle, said member having notches in the other end adapted to receive the brake beam brace rod, and means for retaining said squared end portion in intimate engagement with the flanges of said beam.
- 20 5. A strut for brake beams, comprising the combination with the flanged beam, of a longitudinally slotted member having a box-shaped end formed integral therewith with right angularly disposed intersecting openings in the sides arranged in acute angular relation to the slot adapted to receive the flanged beam, said member having a right angularly notched outer end, the end of said box-shaped end having an opening therein adapted when the beam extends through either of said intersecting openings to register with an opening in said beam, and a fastening bolt extending through the aligned head and beam openings.

DAVID PATERSON.
